(57) **CLAIM**

The ornamental design for a surgical knife safety handle, as shown and described.

DESCRIPTION

FIG. 1 is a perspective view of a first embodiment of a surgical knife safety handle showing our new design, with the guard extended to cover the surgical knife blade; FIG. 2 is a top view of the surgical knife safety handle shown in FIG. 1;

FIG. 3 is a bottom view of the surgical knife safety handle shown in FIG. 1;

FIG. 4 is a left side elevational view of the surgical knife safety handle shown in FIG. 1;

FIG. 5 is a right side elevational view of the surgical knife safety handle shown in FIG. 1;

FIG. 6 is a front elevational view of the surgical knife safety handle shown in FIG. 1;

FIG. 7 is a rear elevational view of the surgical knife safety handle shown in FIG. 1; and,

FIG. 8 is a perspective view of the surgical knife safety handle shown in FIG. 1, with the guard retracted to expose the surgical knife blade.

The broken line showing of the surgical knife blade and blade support is for illustrative purposes only, and forms no part of the claimed design.
